UNITED STATES PATENT OFFICE.

THOMAS J. FEGLY AND GEORGE O. LEOPOLD, OF PHILADELPHIA, PENNSYLVANIA,
ASSIGNORS TO NORTH BRO'S. M'F'G CO., OF PHILADELPHIA, PENNSYLVANIA, A
CORPORATION OF PENNSYLVANIA.

SPIRAL TOOL.

Application filed August 16, 1923. Serial No. 657,755.

To all whom it may concern:

Be it known that we, THOMAS J. FEGLY and GEORGE O. LEOPOLD, citizens of the United States, residing in Philadelphia, Pennsylvania, have invented certain Improvements in Spiral Tools, of which the following is a specification.

This invention relates to certain improvements in spiral tools of the type in which 10 a spiral spindle reciprocates within a tubular casing.

The object of this invention is to provide a simple and effective means for holding the spiral spindle within the casing against 15 the pressure of the projecting spring.

In the accompanying drawings:

Fig. 1 is a side view of a spiral screw driver illustrating our invention;

Fig. 2 is a sectional view of that portion 20 of the screw driver to which our invention relates, the cam ring being in section;

Fig. 3 is a vertical sectional view on the line 3—3, Fig. 2;

Fig. 4 is a sectional plan view on the line 25 4—4, Fig. 3;

Fig. 5 is a sectional plan view on the line 5—5, Fig. 3;

Fig. 6 is a sectional plan view on the line 30 6—6, Fig. 3; showing the cam ring in position to allow the spindle to move freely;

Fig. 7 is a view on the same line as Fig. 6, showing the cam ring shifted to lock the spindle to the casing;

Fig. 8 is a detached perspective view of 35 parts of the mechanism;

Fig. 9 is a view illustrating a modification of the invention;

Fig. 10 is a view, partly in section, illustrating another modification;

Fig. 11 is a sectional view on the line 40 11—11, Fig. 10;

Fig. 12 is a view, partly in section, illustrating still another modification; and

Fig. 13 is a sectional view on the line 45 13—13, Fig. 12.

Referring in the first instance to Figs. 1 to 8 of the drawings, 1 is a hollow casing having a handle 2 at one end and an enlarged section 3 at the opposite end, in 50 which is the ratchet mechanism shown by dotted lines in Fig. 1. This ratchet mechanism is controlled by a shifter 4 in the manner common to this type of tool. The enlargement 3 is enclosed within a shell

5. 6 is a spindle adapted to reciprocate within the casing. This spindle has spiral grooves 8 cut therein, as shown in Fig. 8. At the lower end of the spindle is an annular groove 9, which is adapted to receive a locking key 10 that is moved into position in the groove when it is desired to lock the spindle within the casing. At the extreme end of the spindle is a chuck 11 for holding a screw driver, or drill bit.

The outer end of the enlarged portion 3 of the casing has an internal screw thread, Fig. 2, to which is adapted a thread of a plug 12, which has a central opening for the passage of the spiral spindle 6, Fig. 3. The plug 12 has a groove 13, in which is a spring 14. This spring has a curved enlargement 15 that extends into recesses 16 in the walls of the groove. The spring is confined in position by a cam ring 17, which is wider than the groove and fits the enlarged portion of the plug 12. This portion is cut away, as shown in Fig. 8, to allow for the free movement of the cam portion 18 of the ring 17. The free end of the spring 14 has a lateral portion 19, and also has an extension 19^a, which prevents the spring jumping out of the opening 20. The lateral portion 19 enters the opening 20 in the key 10, which is located in a slot 21 cut in the plug 12. The slot extends into the opening in which the spiral spindle reciprocates so that the key 10, when projected by the cam ring 17, will enter the groove 9 in the spindle, holding it against longitudinal movement. The key is made as 90 clearly shown in Fig. 8, and has a beveled portion 22, in which the cam 18 rests when the cam ring is in the position shown in Fig. 6. When the cam ring is turned to the position shown in Fig. 7, the cam 18 rides upon the edge of the key and forces it into the groove 9 of the spindle. The face of the cam is flat, as shown, and is formed on the ring 17 by crimping the ring, as shown clearly in Fig. 8.

In the ordinary operation of a spiral screw driver, a spring 23, Fig. 1, retracts the handle and the casing. When the handle is pressed forward, the spiral spindle is turned in a given direction, according to 105 the position of the shifter 4. In order to lock the spindle within the casing, as shown in Fig. 1, the key 10 is provided, which, on

turning the cam ring 17, is projected into the groove 9 of the spindle, holding the spindle against the pressure of the spring 23. On reversing the movement of the cam ring, the spring 14 retracts the key 10 and the spring 23 is free to project the spindle.

In Fig. 9, a modification is illustrated, in which the spring 14^a has rounded extensions 19^a, which rest in recesses 16^a in the 10 walls of the plug 12^a, confining the rear end of the spring to the plug.

In Figs. 10 and 11, another modification is shown, in which the inner end of the 15 spring 14^b is bent. This portion of the spring extends under ears 16^b, pressed from the metal of the plug 12^b.

In Figs. 12 and 13, still another modification is illustrated, in which the spring 14^c is clamped to the plug by bars 16^c, confining 20 the rear end of the spring to the plug.

The constructions hereinbefore described are not intricate and the cam ring can be readily manipulated to lock, or unlock, the spindle, when desired.

25 We claim:

1. The combination in a spiral tool, of a casing; a grooved spindle located within the casing; a spring for projecting the spindle; a plug secured to the end of the 30 casing; said plug having an annular groove therein and a slot communicating with the groove; a segmental key mounted in the slot; a spring having enlargements at one end extending into the recesses in the walls 35 of the groove, said spring having a lateral

portion at its opposite end extending into an opening in the key and tending to force the key outwards; and a cam ring having a cam portion acting on the key to project it into the groove of the spindle when the 40 spindle is retracted.

2. The combination in means for locking a spindle to the casing of a spiral tool, of a casing having a plug; a spindle having a groove; a key in the plug arranged to 45 be moved into the groove to lock the spindle, said key having an opening; a spring having a lateral extension projecting into the opening, the opposite end of the spring having a curved enlargement, the plug having a recess to receive the enlargement; and a cam ring enclosing the key and the spring, 50 said cam ring being arranged to act upon the key to force it into the groove of the spindle.

3. The combination in means for locking a spindle to the casing of a spiral tool, of a casing; a plug secured to the casing; a spindle extending through the plug and into the casing and having an annular 60 groove therein; a laterally movable key in the plug; a cam ring for moving the key into the groove of the spring; and a spring, for retracting the key, secured at one end to the plug, said spring having a lateral 65 portion engaging the key and also having a lateral extension, which holds it in engagement with the key.

THOMAS J. FEGLEY.
GEORGE O. LEOPOLD.
